UNITED STATES PATENT OFFICE.

MARY P. E. SALTZMAN, OF WASHINGTON, DISTRICT OF COLUMBIA.

FASTENER.

1,411,188.

Specification of Letters Patent. Patented Mar. 28, 1922.

Application filed February 4, 1920. Serial No. 356,130.

To all whom it may concern:

Be it known that I, MARY P. E. SALTZMAN, a citizen of the United States of America, residing at Washington, in the 5 District of Columbia, have invented a certain new and useful Improved Fastener, of which the following is a specification.

This invention relates to improvements in fastening devices, and it may be stated that 10 the principal object of the invention is to provide a novel and exceedingly simple fastener particularly adapted for use in the securing of trimming to the hats of women in a positive and satisfactory manner, and 15 also, without material effort or difficulty.

Heretofore, in practising millinery, the mode of securing trimming to a hat in the position desired, has been accomplished by 20 first placing such trimming in position upon the hat and then temporarily securing the same thereto with pins, or like devices, whereupon, the trimming is permanently secured by stitching. In carrying out this practise of trimming hats, however, much 25 difficulty is experienced in preventing movement of the trimming with relation to the hat during the sewing of the same in permanent position, it oftentimes occurring even after the trimming has been "permanently" secured, that the same will be permitted 30 to shift to an undesired position on the hat upon the subsequent removal of the pins therefrom. Thus, it will be appreciated, that because of the difficulties outlined, efforts 35 by amateurs in the trimming of hats, possibly their own, will be materially discouraged and in consequence, the services of a milliner sought, thus entailing an expense which by the use of my improved device, will be eliminated.

Another and equally important object of 40 the invention resides in the provision of a fastener, one part of which is formed by a substantial staple like device, the space between the opposite sides of the inner portion 45 of this device being wedge like and in consequence, serving to positively retain material engaged thereby.

Other objects will be in part obvious and 50 in part pointed out hereinafter.

In order that the invention and its mode 55 of application, together with one of its many uses, may be understood by persons skilled in the art, I have in the accompanying illustrative drawings and in the detailed follow-

ing description based thereon, set out preferred embodiments of the invention.

In these drawings:

Figure 1 is a perspective of a hat having the trimming thereof secured by my fasten- 60 ing device.

Figure 2 is a disassembled perspective of the device.

Figure 3 is a section through the hat showing the manner in which the fastener 65 is engaged.

Figure 4 is a disassembled perspective of a slightly modified form of the device.

Figure 5 is a section through the hat showing the modified fastener applied, and 70

Figure 6 is a perspective of a further modification.

Having more particular reference to the drawings, in connection with which like reference characters will designate corresponding parts throughout the several views, my improved fastener comprehends a staple like member 1 formed with diverging sides 2 which are substantially square or rectangular in cross section; the free ends of these 75 diverging sides being pointed in order that the member 1 may be caused to readily penetrate different characters and grades of material. In this connection, it should be noted that by reason of the diverging sides 2 of 80 the staple like member, a wedge like space will occur between the same and therefore, material or trimming engaged by this member will be firmly retained between the diverging sides thereof adjacent its closed or 85 inner end. Furthermore, since a wedging action will occur with the securing of the trimming by the fastener, it will be understood that such trimming will be compressed 90 between the diverging sides of the fastener and in this way, the engagement between said trimming and the fastener will tend to be even more positive.

As means for securing the fastener in 100 position upon a hat and also, to secure trimming held thereby positively in the position desired, a clamping or securing plate 3 is provided, comprising a flat piece of material, preferably a metal corresponding to the metal from which the staple like 105 member 1 is formed, and having spaced rectangular shaped openings 4 therein, which openings, as will be noted, are of a size such as will effect snug reception of the diverging sides or shanks 2. Due to the 110

snug engagement of the sides 2 and the openings 4 in said clamping plate, it follows that relative movement between the member 1 and its clamping plate will be prevented and therefore any tendency of the member 1 to shift with relation to a hat engaged thereby subsequent to the securing of the fastener in an operative position, will be prevented.

10 In using my improved fastening device, reference is had to Figure 3. The trimming to be secured to the hat is engaged in the wedge like space occurring between the inner end of the diverging sides whereupon, 15 the pointed shanks 2 are passed through the desired portion of the hat and arranged adjacent the inner side thereof. At this time, the clamping plate 3 is engaged over the outer ends of the shanks 2 and moved 20 there-along to effect positive connection between the trimming engaged by the fastener and the hat, that portion of the trimming engaged being compressed by reason of its arrangement in the wedge like space here- 25 tofore mentioned and in consequence, positively secured against movement with relation to the hat. With the clamping plate so engaged, the exposed portions of the shanks 2, which of course, are pliable to 30 the desired extent, are bent outwardly at substantially right angles, thus serving to lock the plate 3 in its clamping position.

In the Figure 4, I have shown a possible modification of my invention, consisting as 35 in the first instance, of a staple like member 1' whose opposite sides or shanks 5 are arranged in substantially parallel relation; a wedge like pocket 6 being formed between the same adjacent the inner or closed end 40 of said member 1' by reason of the rounded bending thereof. This pocket also affords a means which will serve to promote positive engagement between the fastener and the trimming to be secured thereby upon 45 a hat, so that when the clamping plate 3' is engaged in its operative position, no shift-

ing of such trimming will occur to detract from the artistic arrangement thereof.

Furthermore, should it be desired, the improved fastener may be employed not only 50 as such but also as an ornament, an ornamental plate, setting or other device 7 being secured to the outer side of the closed end thereof as shown in the Figure 6. With this arrangement, it is obvious that 55 such portion of the fastener as might be exposed, will be covered by the ornament 7 and thereby add to the appearance of the trimmed hat.

Manifestly, the constructions shown are 60 capable of further modification and such modification as is within the scope of my claims, I consider within the spirit of my invention.

I claim:

1. A fastener of the character described comprising a staple-like member formed of pliable material flat in cross section having divergent sides, the extremities of which are pointed and an arcuate basal portion, 70 and a clamping plate having spaced openings therein for snugly receiving the divergent sides whereby with bending of the free portions of said sides into positions substantially parallel to the same, said plate will 75 cooperate with the inner portion of the staple-like member to wedgingly clamp an article between the same.

2. A fastener of the character described comprising a staple-like member formed of 80 pliable material flat in cross section, the extremities of which are pointed and an arcuate basal portion, and a clamping plate having spaced openings therein for snugly receiving the sides whereby with bending 85 of the free portions of said sides into positions substantially parallel to the same, said plate will cooperate with the inner portion of the staple-like member to wedgingly clamp an article between the same.

MARY P. E. SALTZMAN.
